UNITED STATES PATENT OFFICE

SALVATORE ARCIDIACONO, OF FULTON, NEW YORK

SHINGLE CONSTRUCTION

Application filed May 31, 1928. Serial No. 281,767.

This invention relates to shingle roofing and has for its object a shingle construction by which the design of the roofing is varied in uniformity.

5 The invention consists in the novel features and in the combinations and constructions hereinafter set forth and claimed.

In describing this invention, reference is had to the accompanying drawings in which 10 like characters designate corresponding parts in all the views.

Figures 1 and 2 are respectively plan views of the two classes of shingles embodied in my roofing.

15 Figure 3 is a fragmentary plan view of the roofing.

This roofing comprises generally two classes of shingles, the shingles of each class being designed to be arranged end to end in 20 a row, the shingles of one class being arranged alternately with and lapping the row of shingles of the other class; and the shingles of one class being formed at their lower edges with projections and cut-outs of one 25 half of two kinds of geometrical figures, and the shingles of the other class being formed with complementary cut-outs and projections arranged to complete the geometrical figure when brought into juxtaposition 30 with the projections and cut-outs of the shingles of the first class.

1 and 2 designate respectively the two classes of shingles, these being multiple composition shingles of any well known material.

The shingles 1 are arranged in one row while the shingles 2 are arranged in another row lapping the row of shingles 1 and also alternately with the shingles 1 so that they 40 lap the joint between the shingles 1 substantially equally on opposite sides of the joint.

The shingles 1 are provided with semihexagonal projections 3 and semiquadrangular projections 4 with the interposed cut-outs 45 5, 6; the shingles 2 are formed with semi-hexagonal cut-outs 7 and semiquadrangular cut-outs 8 complementary to the projections 3 and 4.

Thus when the shingles are brought into 50 juxtaposition, the hexagonal projections and

cut-outs provide an hexagonal outline, and the semiquadrangular projections and cut-outs provide a quadrangular outline. Hence the roofing is composed of columns of hexagons and quadrangles. The sides of the 55 hexagons of one column form the sides of the quadrangles of the next columns.

The upper edges of both classes of the shingles are straight. Therefore both shingles may be cut from a roll of the material 60 of the proper width at one operation without any waste of material.

What I claim is:

1. A roofing comprising two classes of shingles, cut from a continuous strip of material without waste, the shingles of each class being placeable end to end and the shingles of one class being arranged alternately with and lapping the shingles of the other class, one edge of both shingles being 65 straight, the shingle of one class having at its other edge projections and cut-outs of substantially one half of two forms of geometrical figures, the shingles of the other class having at its other edge complementary 70 cut-outs and projections of the other half of said geometrical figures so arranged that the two classes when brought into juxtaposition, the projections of each with the cut-outs of the other complete the two forms 75 of geometrical figures, and the completed roof forming a plurality of rows of each of said geometrical figures alternately arranged.

2. A roofing comprising two classes of shingles, the shingles of each class being placeable end to end and the shingles of one class being arranged alternately with and lapping the shingles of the other class, one edge of 80 both shingles being straight, the shingle of one class having at its other edge projections and cut-outs of part of a hexagon and of a quadrangle and the shingles of the other class having at its other edge complementary 85 cut-outs and projections so arranged that when the two classes are brought into juxtaposition, the projections of each with the cut-outs of the other form complete hexagons and quadrangles, and the completed 90 roof forming a plurality of rows of each of 100

said hexagons and quadrangles alternately arranged.

In testimony whereof, I have hereunto signed my name at Fulton, in the county of Oswego, and in the State of New York, this 19 day of May, 1928.

SALVATORE ARCIDIACONO.
